UNITED STATES PATENT OFFICE.

SIDNEY GORDON MONK, OF PLYMOUTH, ENGLAND.

PERPETUAL CALENDAR.

1,360,004.

Specification of Letters Patent. Patented Nov. 23, 1920.

Application filed May 11, 1920. Serial No. 380,595.

To all whom it may concern:

Be it known that I, SIDNEY GORDON MONK, a subject of the King of England, residing at Plymouth, in the Kingdom of England, have invented new and useful Improvements in and Relating to Perpetual Calendars, of which the following is a specification.

Perpetual calendars as now in use are characterized by relatively-movable members, either of fabric running over rollers, by rotating disks or by running sliders, having displayed upon them certain selected data, and arranged so that the juxtaposition of these movable members in some particular manner shall produce the calendar for any particular month for any particular year. The manner of obtaining this juxtaposition between the moving members consists, in general, either of (1) bringing certain exhibited data, *e. g.*, years or months, into positions adjacent to one another, the necessary movement bringing about automatically a corresponding movement of the other data, thus exhibiting the desired calendar, or of (2) requiring knowledge, obtained from some external source, of the desired calendar, and merely setting the data provided into that particular form, or of (3) using an auxiliary code, provided with the calendar, by the aid of which the desired setting is accomplished.

My invention described in particular, relates to that system of calculating and indicating dates by means of perpetual calendars wherein certain year numbers, months, month-dates, and days are arranged on certain relatively-movable members so as to coöperate with one another in some particular manner, thereby producing a calendar for any selected month, and more particularly to that class of calendar that is set by effecting relative adjustment between scales or tables:—

(1) day names (a single set), (2) month names in specific groups. (3) dates of the month (a double set in prescribed positions), (4) year-numbers in specified groups in seven columns adapted to correspond with the day names. In such calendars the table of years provided is capable of indefinite extension, as indicated hereinafter. The method of setting employed requires no auxiliary code, involving but a simple movement, namely, the bringing together of the month required (on one member), and

the year selected (on another member), producing finally a calendar of the familiar variety, with the days of the week in order, beginning with Sunday. 60

The present invention consists in a particular method of carrying out this system, employing straight running sliders for the adjustable parts, and residing in the particular combination and arrangement of 65 parts for this purpose hereinafter described.

Although the use of running sliders has been proposed in other forms of perpetual calendar, such forms do not make use of the particular method of setting herein employed. 70

The invention is illustrated in the accompanying drawings, of which:—

Figures 1 and 2 represent face plans of the component parts and Fig. 1^a represents 75 a section through X—Y of the assembled parts.

The invention consists of a face sheet A Fig. 1 upon which is set out a succession of years as shown *a*, the succession being 80 capable of extension in either direction, subject only to the condition that the years be arranged in rows of seven and that a blank space be left immediately preceding every leap year. Alongside this table of 85 years an opening or "window" *b* is cut out of the sheet, in order to display another table on a slide behind (shortly to be described). Against this again is set out the days of the week *c* as shown, Fig. 1, beside 90 a second opening or "window" *d* cut out of the sheet to display another table on the slide aforementioned.

A slide B, Fig. 2, shall be mounted in runners behind the face sheet A, Fig. 1, and upon this slide shall be set out two tables *e* and *f* (shortly to be described) and the slide so mounted that these tables are accurately displayed through the windows *b* and *d* respectively in the face sheet A, 100 Fig. 1. The table *e* above referred to shall comprise the months of the year set out in seven rows and the succession of rows repeated as necessary to total 13, as specifically shown. Table *f*, shall comprise the 105 succession of numbers 1 to 31, arranged in successive order as specifically shown.

When the calendar is assembled, with, slide B, in position behind face sheet A, as defined and shown in section in Fig. 1^a, and when slide B, is moved so that any selected month in table *e*, is opposite any selected

year in table *a*, then there will be displayed, through window *d*, the ordinary calendar for that selected month for that selected year, on a portion of table *f* Fig. 2.

5 It is not necessary that the beginning of the particular sequence of years in table *a* Fig. 1 and of months in table *e* Fig. 2 be observed always as herein specifically defined. A calendar wherein a year other than 10 1912 were the first in table *a*, and a corresponding month (or months) the first column of table *e*, would be deemed to be a cognate form of this invention. For example if 1921, be the first year in table *a* 15 Fig. 1 and the "January and October" column the first in table *e* Fig. 2, such a calendar would give the same reading as the one specifically defined and drawn. The inter-relation between the years in table *a* 20 and the months in table *e* is such that whatever year be selected with which to begin table *a*, the column selected to begin table *e* must be the one containing the month or months in that year in which the first day 25 falls upon a Saturday.

In table *e* January and February are re-

peated in adjacent columns in a specially distinguished way, *e. g.*, by being displayed in special characters or in a special colored ink, and these special months are intended for use in leap years only. The leap years are also distinguished in table *a* by some special characteristic, *e. g.*, lined around in red ink or such like manner.

30 I claim:

35 A calendar consisting in a face plate bearing on its front 4 columns of year numbers showing a blank space before the leap year numbers, a sight aperture next to the number columns, a laterally adjoining single day column followed by an adjacent lateral sight aperture, and vertical runners applied to the rear of the face plate in combination with a slide adapted to move vertically in 40 said runners and bearing thirteen rows of 45 months and thirteen spaced aligned rows of day-numbers arranged so as to appear within said apertures in successive alinement with the year numbers on the face plate.

24th April, 1920.

SIDNEY GORDON MONK.
